US00D990018S

(12) **United States Design Patent** (10) **Patent No.:** **US D990,018 S**
(45) **Date of Patent:** **** Jun. 20, 2023**

(54) **SOLAR LAMP**

(71) Applicant: **SHENZHEN YUANMINGYANG TECHNOLOGY CO., LTD.**, Shenzhen (CN)

(72) Inventor: **Cui Shang**, Nanyang (CN)

(73) Assignee: **SHENZHEN YUANMINGYANG TECHNOLOGY CO., LTD.**, Shenzhen (CN)

(**) Term: **15 Years**

(21) Appl. No.: **29/882,226**

(22) Filed: **Jan. 12, 2023**

(51) LOC (14) Cl. **25-03**

(52) U.S. Cl.

USPC **D26/67**

(58) **Field of Classification Search**

USPC D26/4, 51, 57, 67-70, 73, 93-94, 101, D26/110

CPC F21V 21/0824; F21V 23/0464; F21V 33/0028; F21V 7/0075

See application file for complete search history.

(57) **CLAIM**

The ornamental design for a solar lamp, as shown and described.

DESCRIPTION

FIG. 1 is a perspective view of a solar lamp showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the solar lamp shown in a closed configuration; and,

FIG. 10 is an enlarged detail view of the selected portion 10 in FIG. 1.

The dash-dash broken lines in the drawings depict portions of the solar lamp that form no part of the claimed design. The dot dash broken lines represent the boundary of the enlarged portion and form no part of the claimed design.

1 Claim, 10 Drawing Sheets
